UNITED STATES PATENT OFFICE.

EZRA C. FITCH, OF NEWTON, MASSACHUSETTS, ASSIGNOR TO WALTHAM WATCH COMPANY, OF WALTHAM, MASSACHUSETTS, A CORPORATION OF MASSACHUSETTS.

DIAL WITH YIELDING FOOT FOR TIMEPIECES.

Application filed July 31, 1925. Serial No. 47,207.

This invention relates to the dials of time pieces, particularly of watches, or other instruments having dials which are fitted with projections, called feet, for attaching the dial to the support on which it is mounted. In the case of watches, the part on which the dial is mounted is the pillar plate, or base plate; a massive plate in and on which are mounted bearings for the movable parts of the watch, and the bridges and other structural parts of the watch movement. In the following description I will generally refer to the instrument as a watch, and to the dial provided with the invention as a watch dial, doing so for convenience and without intending thereby to set limits to the invention or to the protection which I claim.

Heretofore in the art of watch making the dial feet have been solid studs or pins made by securing pieces of wire in the dial plate; such feet being adapted to enter complementary holes in the pillar plate and be secured by set screws placed in the edge of the pillar plate. In order to make a secure connection between the dial feet and such set screws, the screws have been pointed at their ends and the dial feet formed with complementary sockets in their sides adapted to receive such pointed screw ends. But the formation of such sockets at the right location in structural members of such small dimensions as the feet of watch dials has been a matter of much difficulty; while if such sockets are omitted, or incorrectly placed, security of attachment is obtained only by driving the holding screws against the dial feet with excessive force. The force so applied is liable to bend the dial and crack the enamel with which such dials are usually faced, owing to the fact that the holes in the pillar plate are larger than the dial feet, and that the metal plate which forms the body of the dial is far less rigid than the enamel facing. Even a slight displacement of a watch dial foot laterally in its hole in the pillar plate, thus caused by pressure of its holding screw, is sufficient to crack the enamel.

My purpose has been to eliminate the difficult operation of previously forming sockets or recesses in dial feet to receive the holding screws, and to enable such holding screws to form their own sockets in the dial feet, with-

out liability of bending the dial and cracking the enamel. I have accomplished this result by making the dial feet of a novel construction such that they have yielding walls, at least at the side next to the screw, so that the latter when set up will indent the adjacent foot without applying to the dial plate, through the foot, a force great enough to crack the enamel.

Referring to the drawings in which I have illustrated the present invention:

Fig. 1 is a fragmentary sectional view on an enlarged scale of a pillar plate and dial of a watch, the plane of section passing through one of the dial feet and its holding screw;

Fig. 2 is a side elevation on a larger scale of a dial and its foot, embodying the invention, in position to be indented by the holding screw;

Fig. 3 is a sectional view of the same, showing the screw as having formed its socket by indenting the side of the foot;

Fig. 4 is a fragmentary plan view as seen from beneath the assemblage shown in Fig. 3;

Fig. 5 is a view similar to Fig. 4 illustrating a modified form of a dial foot embodying the same invention.

Like reference characters represent the same parts wherever they occur in all the figures.

In Figure 1 *a* represents a fragment of the pillar plate of a watch, in one face of which is a recess, surrounded by a lip *b*, to receive the dial. In all figures *c* represents the body or base plate of the watch dial, *d* a facing of enamel on the dial, and *e* one of the dial feet. Such dial may be made of any materials, and in any manner heretofore known or used in the watch making art, and the foot may be applied and secured to the dial in any usual, or other suitable manner. No change is made by this invention in the construction of the dial itself or in the mode of mounting the foot upon the dial; while on the other hand dial feet containing this invention may be applied in connection with new constructions and characteristics which may hereafter be developed in dials and methods of attaching their feet. *f* represents the dial foot screw which is set into the edge part of the pillar plate in a tapped hole which enters the hole provided in the side

of the plate to receive the dial foot. Such screw is here shown as pointed at the end, as usual.

The new step of the invention consists in making the dial foot of such yielding construction that it may be indented and offset in that part against which the dial screw bears. For this purpose the foot is preferably made as a tube of copper or other suitable material. Materials are suitable for the purpose which, in tubular form, have sufficient flexibility and ductility to be indented in the manner indicated without being broken, and at the same time are stiff enough to remain in approximately the original form all around the indented area, and also have durability and tensile strength sufficient for the purpose of a dial foot, but are not rigid enough to transmit bending stresses to the dial plate sufficient to crack the enamel facing. These facings are strong enough to resist bending and tensile stresses of certain values, but not enough to resist the forces which may be applied by dial foot screws to solid dial feet in holes of the relative proportions commonly used in watch making. I have found that copper tubes of the same diameters as the prior solid dial feet, and with a ratio of thickness of wall to diameter substantially equal to that shown in these drawings, when cut to suitable length and applied to a dial as a foot thereof, have the required yielding quality and strength.

When the holding screw is set up against a dial foot so made, its point displaces the wall of the foot at and near the point of engagement only, substantially as shown in Figure 3, indenting and drawing the metal, whereby the point of the screw forms its own socket, without applying so much force to the foot as would cause injury to the dial.

The dial foot above described is an open tube. In Figure 5 I have shown a modified form of the foot made as a cup, having a wall e' at the outer end of the foot. The side walls of this form of foot are yielding in substantially equal measure with those of the first described tubular form, but the end wall braces the side walls at their outer end and insures that when the foot is indented by the screw, enough stock will remain outstanding between the end of the foot and the under side of the dial screw to prevent the foot being accidentally withdrawn.

It is to be understood that the locally yielding character of the foot made according to my invention is due to the fact that the foot is made as a hollow body and that the yielding portion is a wall bounding one side of the interior space. Such hollow formation may be obtained in a variety of ways, as by drawing out the stock from which the foot is made as a tube or a cup in the first place and also by drilling lengthwise into a solid rod or wire, and otherwise.

What I claim and desire to secure by Letters Patent is:

1. The combination with an enamel faced dial and a support therefor, of means for securing the dial to the support comprising a hollow foot projecting from the back of the dial into a hole in the support, and a pointed screw set into the support protruding at its pointed end into said hole; the wall of the hollow foot being so thin and ductile and the point of the screw so sharp that the latter will indent and penetrate the former without transmitting so great bending stress to the dial as will crack the enamel facing thereof.

2. A metal dial having a facing of enamel and a tubular metal attaching foot projecting from its back, the wall of said foot being so thin and flexible that, when pressed upon laterally by the point of a sharp-pointed screw, it will fail before transmitting a great enough bending strain to the dial to crack said facing.

3. A dial having a facing of enamel and a foot projecting from its back, said foot being of hollow construction with walls of such ductility and thinness, in proportion to the stiffness of the dial to resist bending, that the pressure applied laterally by the point of a pointed set screw to the foot will indent the side thereof without transmitting sufficient bending strain to the dial to crack said facing.

4. The combination of a dial having an enamel facing, a hollow foot projecting from the back of the dial, and a pointed set screw arranged to be forced, point foremost, against the side of said foot; the wall of the foot being so ductile and tenuous that it will be penetrated by said point without transmitting enough bending strain to the dial to crack said enamel facing.

In testimony whereof I have affixed my signature.

EZRA C. FITCH.
